UNITED STATES PATENT OFFICE.

REUBEN C. BAKER, OF COALINGA, CALIFORNIA, ASSIGNOR TO BAKER CASING SHOE COMPANY, A CORPORATION OF CALIFORNIA.

WELL-DRILL-PIPE FLOAT COUPLING.

Application filed December 1, 1926. Serial No. 151,862.

This application is a continuation of a prior application entitled Well drill pipe float coupling, Ser. No. 1,942, filed January 12, 1925.

5 The present invention relates to an improved drill pipe float coupling and contemplates the provision of a float coupling which is fitted with a back pressure valve mechanism permitting the string wherein it 10 is interposed to be "floated" into place in a well to relieve derrick strains. This valve mechanism is constructed to permit free passage of circulating fluid through the string and eliminates the danger of plugging the 15 water course in the event that the valve member proper should accidentally become detached from its associate mechanism.

One form which the invention may assume is exemplified in the following description 20 and illustrated by way of example in the accompanying drawing, in which:

The figure is a view in vertical section through a well drill coupling embodying the preferred form of my invention.

25 Referring more particularly to the accompanying drawings, 10 indicates a cylindrical drill pipe coupling used when drilling wells to couple the contiguous ends of drill pipe sections. The coupling 10 is hollow so that 30 circulating fluid may be passed therethrough to the drill. At its upper end the coupling is interiorly threaded to receive the threaded end of a drill pipe section 12. At its lower end the coupling is reduced in diameter and 35 exteriorly threaded so that it may be threadedly connected with the adjacent end of a drill pipe section 14.

It will be noticed that at the reduced lower 40 end of the coupling, the chamber is also reduced in diameter to form an interiorly projecting annular shoulder 15.

Intermediate the ends of the coupling a threaded bore 16 is formed which is less in diameter than the chamber extending inwardly from the female end of the coupling. At the lower end of the bore an interiorly projecting annular shoulder 17 is formed.

The threaded bore 16 is adapted to receive a valve cage 18 which is in the form of a 50 cylindrical sleeve having a valve seat 19 formed at its lower end and a bridge 20 at

its upper end. The valve seat is formed at the inner periphery of the lower end of the sleeve, and is adapted to cooperate with a flat valve member 21. This valve member 55 is formed with a centrally located boss 22 which projects downwardly from the bottom of the valve. A valve stem 23 is fixed at its lower end within the valve and boss and extends upwardly through a guide opening 60 in the bridge 20. This latter is a narrow flat member extending diametrically between the side wall of the cage, as illustrated.

The valve stem 23 projects a considerable distance above the bridge and is fitted with 65 a nut 24 at its upper end. A compression spring 25 is interposed between this nut and the bridge to normally maintain the valve seated.

To eliminate unnecessary wear of the 70 spring 25, a hollow sleeve 26 is loosely arranged over it on the stem. This sleeve 26 rests on the bridge and projects upwardly short of the nut 24. The distance between the nut and the upper end of the sleeve 26 75 represents the amount which the valve may open as the nut will abut against the sleeve upon the opening of the valve and limit the opening thereof.

If by chance the valve 21 should become 80 detached from the stem or should the bridge or stem be broken, the valve will not plug the string. This is due to the provision of a plurality of downwardly projecting lugs 27 formed on the bottom of the valve 21 85 and spaced apart adjacent its periphery. These lugs 27 will rest on the shoulder 15 in the coupling and prevent the valve from seating on top of the shoulder and plugging the water course. The downwardly projecting boss 22 on the valve acts to prevent the valve from inverting.

In operation of the device, the coupling is constructed and fitted with the valve mechanism as described. In running in the 95 string the valves will close and permit it to be "floated" into position. Exhaustive tests have proven that this will double the life of the wire lines and brake bands and relieve excessive strains on other derrick 100 equipment.

When positioned, circulating fluid may be

pumped downwardly through the string. The pressure of the fluid will open the valve. The present device will permit perfect circulation at all times due to the unobstructed 5 valve cage and enlarged chamber below the valve which affords free passage of the fluid through the valve.

There is nothing but a small valve stem 10 guide in the cage for anything to hang upon, and the four lugs at the bottom of the valve prevent the valve from seating on the shoulder 17 and plugging the water course, if by chance the valve stem or other parts should break and release the valve.

15 By its construction the valve and cage may be expeditiously removed for inspection, repairs or replacements.

While I have shown the preferred form 20 of my invention, it is to be understood that various changes may be made in its construction by those skilled in the art without departing from the spirit of the invention, as defined in the appended claims.

Having thus described my invention, what 25 I claim and desire to secure by Letters Patent is:

1. A drill pipe float coupling comprising a cylindrical coupling adapted to connect aligned sections of drill pipe, said coupling 30 having a central chamber formed longitudinally therethrough, said chamber being reduced in diameter at one end of the coupling forming an annular shoulder within the coupling, a valve cage detachably secured with- 35 in the chamber of the coupling, said valve cage having a valve seat, a valve guided by said cage for cooperation with the seat to control the passage of fluid through the coupling, said valve opening toward the reduced 40 end of the chamber, and means on the valve adapted to engage with said shoulder to prevent the valve from interrupting the flow of liquid through the coupling in the event that the valve should become disengaged 45 from the valve cage.

2. A drill pipe float coupling comprising a cylindrical coupling adapted to connect aligned sections of drill pipe, said coupling having a central chamber extending longi- 50 tudinally therethrough, said chamber being reduced in diameter at one end of the coupling forming an annular shoulder within the coupling, a valve cage threaded within the chamber of the coupling intermediate its 55 ends, a valve seat formed at one end of said cage, a valve guided in said valve cage for cooperation with said seat to control the passage of fluid through the coupling, said valve opening toward the reduced end of the 60 chamber in the coupling, spaced lugs on said valve adapted to engage with said annular shoulder to prevent the valve from interrupting the flow of liquid through the coupling in the event that the valve should be- 65 come disengaged from the valve cage.

3. A drill pipe float coupling comprising a cylindrical coupling adapted to connect aligned sections of drill pipe, said coupling having a central chamber formed longitudinally therethrough, said chamber being reduced in diameter at one end of the coupling forming an annular shoulder within the coupling, a valve cage detachably secured within the chamber of the coupling, said valve cage having a valve seat, a valve 70 guided by said cage for cooperation with the seat to control the passage of fluid through the coupling, said valve opening toward the reduced end of the chamber, and means on the valve adapted to engage with said shoulder to prevent the valve from interrupting the flow of liquid through the coupling in the event that the valve should become disengaged from the valve cage, means for preventing the valve from inverting within the 75 chamber.

4. A drill pipe float coupling comprising a cylindrical coupling adapted to connect aligned sections of drill pipe, said coupling having a central chamber extending longitudinally therethrough, said chamber being reduced in diameter at one end of the coupling forming an annular shoulder within the coupling, a valve cage threaded within the chamber of the coupling intermediate its ends, a valve seat formed at one end of said cage, a valve guided in said valve cage for cooperation with said seat to control the passage of fluid through the coupling, said valve opening toward the reduced end of the chamber in the coupling, spaced lugs on said valve adapted to engage with said annular shoulder to prevent the valve from interrupting the flow of liquid through the coupling in the event that the valve should become disengaged from the valve cage, and means for preventing the valve from inverting within the 80 chamber.

5. A well drill pipe float coupling comprising an elongated cylindrical coupling adapted to be connected at its ends to aligned sections of drill pipe, a central chamber formed centrally and longitudinally through the coupling, said chamber being reduced in diameter at one end forming an annular shoulder within the coupling, a threaded bore in the coupling of a diameter slightly less than the diameter of the body portion of the chamber therein, a sleeve threaded in said bore, said sleeve having a valve seat formed at its end adjacent the reduced end of the chamber, a bridge extending diametrically of the sleeve, a valve adapted to seat against said seat, a valve stem secured at one end to the valve and extending upwardly through the sleeve and guided through the bridge, a nut at the end of the valve stem, a compression spring between the nut and the bridge whereby the spring will normally maintain said valve 85 90 95 100 105 110 115 120 125 130

seated, said valve opening toward the reduced end of the chamber, a projection extending axially from the valve member to prevent the latter from inverting should it become disconnected from its stem and sleeve, spaced lugs on the valve projecting toward the reduced end of the coupling, said lugs adapted to engage said annular shoulder should the valve become disconnected from its stem and sleeve to prevent the valve from interrupting the flow of liquid through the coupling.
